CLAIM

The ornamental design for a ball holder, as shown and described.

DESCRIPTION

FIG. 1 is a perspective view of a ball holder showing my new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a perspective view of the ball holder of FIG. 1 in a partial open position;

FIG. 7 is a perspective view of the ball holder of FIG. 1 in a complete open position;

FIG. 8 is a top plan view of the ball holder of FIG. 1 in a complete open position;

FIG. 9 is a bottom plan view of the ball holder of FIG. 1 in a complete open position;

FIG. 10 is a left side elevational view of the ball holder of FIG. 1 in a complete open position; the opposite side being a mirror image;

FIG. 11 is a perspective view of the ball holder of FIG. 1 in a partial open position, showing a tennis ball therein in phantom;

FIG. 12 is a perspective view of the ball holder of FIG. 1, showing a lock in phantom; and,

FIG. 13 is a perspective view of the ball holder of FIG. 1, showing a dog in phantom.

The broken line showing is for environmental purposes only and forms no part of the claimed design.
